UNITED STATES PATENT OFFICE.

FRANK B. STICKLER, OF BOSTON, MASSACHUSETTS.

FASTENING DEVICE.

1,036,568.

Specification of Letters Patent.

Patented Feb. 19, 1914.

Application filed December 6, 1912. Serial No. 735,192.

To all whom it may concern:

Be it known that I, FRANK B. STICKLER, a citizen of the United States, residing in Boston, county of Suffolk, and State of Massachusetts, have invented an Improvement in Fastening Devices, of which the following description, in connection with the accompanying drawings, is a specification, like letters on the drawings representing like parts.

This invention relates to a fastening device especially adapted among other uses, to be employed on automobiles, boats, and the like for fastening curtains, covers and like parts in place.

The invention has for its object to provide a simple, inexpensive and efficient device, for the purpose specified. To this end, the fastening device comprises a male member of novel construction, as will be described, and a female member, which is preferably of novel construction, as will be described.

Figure 1 is an elevation of a fastening device embodying this invention. Fig. 2, a section on an enlarged scale, taken on the line 2—2, Fig. 1. Fig. 3, a view like Fig. 2, showing the female member in the act of being slipped onto the male member. Fig. 4, a section on the line 4—4, Fig. 3, looking in the direction of the arrow thereon. Fig. 5, a section on the line 5—5, Fig. 2, and Fig. 6, a detail of one of the locking devices to be referred to.

Referring to the drawing, the male member herein shown comprises a base plate *a* having extended from it a hollow body portion *b* normally open at its upper and lower ends. The hollow body portion *b* may and preferably will be made of sheet metal integral with the base *a* and struck up therefrom to form a cylinder having at its lower end an annular shoulder 10, see Fig. 2, against which a disk or plate 12 is held by suitable prongs or clips 13, or otherwise, see Fig. 4. The disk or plate 12 serves as a support for holding devices, which coöperate with the female member, to be described, to retain the same on the body portion *b*, and further serves as a guide for a stem or rod 14 extended from the under side of a head 15, which closes the upper or outer end of said cylindrical body portion. The holding devices referred to, are located substantially diametrically opposite, and each comprises a shank or arm 16, having at its lower end a reduced portion 17, which fits loosely in a slot 18 in the disk or plate 12, and also having a cross piece or head 19 which engages the under side of the disk or plate 12. The slots 18 extend inwardly from the circumference of the disk or plate 12, which enables the narrow portions or webs 17 to be slipped into them before the disk or plate 12 is secured against the annular shoulder 10. Each arm 16 is provided with a finger 20, which is provided with a downwardly inclined or beveled upper surface 21 and preferably with an under cut or inclined lower surface 22, for a purpose as will be described. The arms 16 are located within the hollow body *b*, and their fingers are extended from within the same to the outside thereof through slots 24 in the upper portion of the hollow body *b*, and said fingers are normally pressed outwardly so that their ends project outside of said hollow body, by a spring, herein shown as a coil of wire 25 having arms 26, which are connected with the arm 16. In the present instance, the arms 26 of the spring are extended into holes 27 in the holding arms 16. The fingers 20 have coöperating with their inclined upper surface 21, an inclined or beveled under surface 28 of the head 15, which is of substantially the internal diameter of the cylinder *b*, and is preferably provided with a curved outer surface so as to form a neat and finished head for said cylinder. The head 15 is movable in its cylinder *b* in one direction by pressure applied to its outer surface, and in the other direction by the beveled surfaces 21 of the fingers 20 coöperating with the beveled under surface 28 of the head, the arms 16 being moved outwardly by the spring 25. The head 15 is guided in its movement by the stem 14 moving through the plate or disk 12, and the said head is prevented from being dislodged from the cylinder *b*, when the latter is inverted in handling, by a flange 30 on the stem engaging the disk or plate 12. The female member comprises as herein shown, two rings 31, 32 between which the curtain 33 or other fabric is clamped, and a cylindrical hub 34, which may be integral with one of said rings and provided with a flange 35, which overlaps the other ring. The upper or outer ring 35 may and preferably will be provided on its upper or outer surface with a beveled lip or flange 37, which coöperates with the under cut surfaces 22

of the fingers 20, to more securely hold the female member on the male member.

When the fastening device is used on an automobile, boat or the like, the base plate *a* is secured to a stationary part 40 of the automobile, boat or the like, and the female member is secured to the curtain, flap or the like 33, which is to be secured in place. The female member is merely slipped over the hollow body portion *b*, and during this movement, the holding devices 16 have their upper ends forced inwardly as represented in Fig. 3 by the engagement of the female member with the inclined upper surfaces 21 of the holding devices. When the female member has passed by the fingers 20, the holding devices 16 are moved by the spring 25, 26 into their vertical position shown in Fig. 2, and the fingers 20 are extended over the female member and serve to firmly hold the latter on the male member. To release the female member, the head 15 is pressed upon by the thumb or finger of the operator, and pushed into the hollow body *b* sufficiently to cause the inclined under surface 28 of the said head, to act against the inclined surfaces 21 of the fingers and force the latter back into the body portion *b*, and thus withdraw them from engagement with the female member and permit the latter to be slipped off of the hollow body *b*.

The holding devices have an oscillating movement and are practically pivoted to the disk or plate 12, which is effected by the narrow web 17 fitting the slot 18 loosely and by the head 19 and shoulder 42 being separated a sufficient distance to permit the arms 16 to oscillate.

I have herein shown one construction of fastening device embodying the invention, but it is not desired to limit the invention to the particular construction shown.

Claims.

1. In a fastening device of the character described, in combination, a male member comprising a hollow body portion open at its upper end and provided with slots near said upper end, holding devices within said body portion and provided with fingers normally extended through said slots and having inclined upper surfaces, means for yieldingly holding said devices in their normal position, a head movable into said hollow body portion and provided with an inclined under surface which engages the inclined upper surfaces of said fingers to move the latter into the hollow body and permit a female member to be removed from the hollow body portion, a stud attached to the under side of said head and extended into said hollow body portion, and means coöperating with said stud to limit the outward movement of said head, substantially as described.

2. In a fastening device of the character

described, in combination, a male member comprising a cylindrical body portion open at its upper end, arms pivoted within said body portion and having fingers normally extended outside of the same and provided with inclined upper surfaces; a movable head to close the open end of said cylindrical body portion and having an inclined under surface coöperating with the inclined upper surfaces of said fingers, means for connecting said head with said body portion to move therewith and to permit movement of the head independently of said body portion to enable the inclined surface of the head to engage the inclined surfaces of the fingers and move the latter within the said body portion and permit a female member to be removed from said body portion, substantially as described.

3. In a fastening device of the character described, in combination, a male member comprising a hollow body portion having slots in its upper end, a disk secured to said body portion at one end and provided with slots extended from its circumference and with a central opening, means for securing said disk to said body portion, arms provided at their lower ends with reduced portions which are inserted in the slots of said disk and having a head and shoulder to engage the opposite sides of said disk, fingers on said arms normally extended through the slots in said body portion and provided with inclined upper surfaces, a spring to hold said arms in their normal position, and a head provided with an inclined under surface to engage the inclined upper surfaces of said fingers, and provided with a stem extended through said disk, substantially as described.

4. In a fastening device of the character described, in combination, a male member provided with a hollow body portion open at its upper end, arms within said body portion having fingers extended outside thereof and provided with upper and lower inclined surfaces, a head to close the open end of and movable in said hollow body portion and having an inclined lower surface which coöperates with the inclined upper surfaces of said fingers and provided with a stem extended within the hollow body portion, means for guiding said stem and for connecting the movable head with the said hollow body portion, and a female member fitted over the male member and having an inclined lip which engages the inclined under surfaces of said fingers, substantially as described.

5. In a fastening device of the character described, a hollow body portion open at its upper end, a holding device within said body portion and provided with a finger extended outside thereof and having an inclined upper surface, and a head for said

hollow body portion movable therein and having an inclined under surface which coöperates with the inclined upper surface of said finger to move the latter into the hollow body portion by movement of the said head, a stem attached to said head and extended into the hollow body portion, and means within the hollow body portion for guiding the said stem, and for connecting

the stem and head to the body portion, substantially as described.

In testimony whereof, I have signed my name to this specification in the presence of two subscribing witnesses.
